UNITED STATES PATENT OFFICE.

WILLIAM J. ELLIS, OF ANDREWS, NORTH CAROLINA, ASSIGNOR OF ONE-HALF TO COLUMBUS W. SAVAGE, OF ANDREWS, NORTH CAROLINA.

STEAM-BOILER FURNACE.

No. 870,090.

Specification of Letters Patent.

Patented Nov. 5, 1907.

Application filed March 1, 1906. Serial No. 303,698. Renewed September 12, 1907. Serial No. 392,571.

To all whom it may concern:

Be it known that I, WILLIAM J. ELLIS, a citizen of the United States, residing at Andrews, in the county of Cherokee and State of North Carolina, have invented 5 certain new and useful Improvements in Steam-Boiler Furnaces; and I do declare the following to be a full, clear, and exact description of the invention, such as will enable others skilled in the art to which it appertains to make and use the same.

10 My invention relates to improvements in steam boiler furnaces, and consists in the novel construction, combination and arrangement of devices hereinafter described and claimed.

One object of the invention is to provide an efficient 15 and economical furnace of this character, in which the fuel will be continuously fed to the grate from a magazine which is located around the boiler so that the heat from the latter will turn the coal into coke before it reaches the grate.

20 Another object of the invention is to provide a furnace of this character having a fuel magazine with means for supplying air to the grate so that perfect combustion results.

A further object of the invention is to improve and 25 simplify the construction and operation of furnaces of this character and thereby render the same more efficient and economical.

The above and other objects which will appear as 30 the nature of the invention is better understood, are accomplished by the construction illustrated in the accompanying drawings, in which:—

Figure 1 is a front elevation of my improved steam boiler furnace; Fig. 2 is a vertical longitudinal sectional view through the same; Fig. 3 is a vertical 35 transverse sectional view taken on the plane indicated by the line 3—3 in Fig. 2, and Fig. 4 is a detail horizontal sectional view.

Referring to the drawings by numeral, 1 denotes my improved steam boiler furnace, the boiler 2 of which 40 is of cylindrical form and is mounted horizontally in the body 3 of the furnace, which is preferably constructed of masonry. As shown, the furnace body 3 consists of two side walls 4, front and rear end walls 5—6 and a top 7, the side and end walls being built upon a suitable foundation 8. The boiler 2, which is in the 45 form of a hollow cylindrical shell, extends through the end walls 5—6 and is arranged centrally in a space formed between the side walls 4 and a horizontal partition 8^a within the body 3. The lower portion 9 of this surrounding space forms the fire-box or combustion chamber of the furnace, and the upper portion 11 forms a fuel magazine or receptacle. The fire-box 9 extends longitudinally the full length of the furnace and its

sides slope downwardly and inwardly to a centrally located longitudinally extending grate 12 arranged above a longitudinally extending ash-box 13 formed between two vertical longitudinally extending partitions 14—15 provided beneath the horizontal partition 8^a and the furnace foundation. These partitions form between their outer faces and the inner faces of the 60 lower portions of the side walls 4, longitudinally extending air passages or chambers 16—17, which are in communication with the central chamber or space 13 through transverse recesses or openings 18 formed in the lower portions of the partitions 14—15. These 65 transverse openings 18 in the two partitions are preferably arranged out of alinement with each other, as shown.

In the front walls of the furnace body are formed openings 19 which align with the air passages 16—17 and 70 which are closed by doors 20. The latter are hinged as at 21, and are provided with suitable latches to hold them closed. In the front wall 5, between the openings 19, is formed an opening 22 which aligns with the central air chamber or ash-box 13 and through which ashes 75 are removed from the furnace. A door 23 is hingedly mounted at 24 to close the opening 22, as shown in Fig. 1. In the front wall 5 is also formed an opening 25, which is disposed slightly above the top of the grate 12 and which is closed by a hinged door 26. Suitable 80 openings 27 are provided in the top 7 of the furnace body, so that coal or other fuel may be discharged into the magazine or receptacles 11, and said openings are closed by doors 28, as shown in Fig. 3.

The steam boiler 2 comprises outer and inner cylindrical shells 29—30, which are connected together at their ends and in the bottoms of which is formed a longitudinally extending opening 32, through which the flames and products of combustion from the fire upon the grate pass into the inner shell and from thence out 90 through its open rear end, its forward end being closed by a head 33. A suitable steam dome 34 is provided upon the top of the boiler, and if desired, a steam gage may also be provided.

The construction, operation and advantages of the invention will be readily understood from the foregoing 95 description taken in connection with the accompanying drawings. It will be seen that the coal fed into the top of the magazine 11 will drop downwardly between the boiler and the side walls of the furnace and be supplied to the grate 12 in the form of coke, the heat from the fire and boiler causing the change. By providing the longitudinal air passages 16—17 upon each side of the central passage or ash pit 13, air will be distributed 100 equally to all portions of the grate, so that the fire upon the same will burn readily and will not be choked by

2
the fresh fuel passing downwardly around the boiler. The opening 32 in the hollow boiler being disposed directly above the grate 12 causes the flames to spread throughout the inner shell of the boiler and effectively 5 heat the water within the same.

Various changes in the form, proportion and the minor details of construction may be resorted to without departing from the principle or sacrificing any of the advantages of the invention, as defined by the appended 10 claims.

Having thus described my invention, what I claim as new and desire to secure by Letters Patent is:—

15. 1. A steam boiler furnace comprising a body having a centrally-disposed, longitudinally-extending ash pit, longitudinally-extending passages upon opposite sides of said ash pit and in communication therewith, a combustion chamber and a fuel magazine forming the upper portion of said body, a grate above said ash pit, and a boiler in the

upper portion of said body, having a flue opening through its bottom and disposed above said grate. 20

2. A steam boiler furnace comprising a body having side and end walls, a horizontal partition 8^a and vertical partitions 14, 15, forming a central ash pit 13, and longitudinal air passages 16, 17, and having openings to establish communication between the ash pit and said air passages, a combustion chamber 9, a fuel magazine 11, a grate in the partition 8^a, above the ash pit, doors to close the open front ends of the ash pit and air passages, and a steam boiler arranged horizontally in the fuel magazine 11 and combustion chamber 9 and having a longitudinally-extending flue opening through the bottom thereof and above said grate, substantially as described. 25 30

In testimony whereof I have hereunto set my hand in presence of two subscribing witnesses.

WILLIAM J. ELLIS.
